STAPLING MACHINE

John T. Kilbride, Bridgeport, Conn., assignor to
 E. W. Carpenter Manufacturing Company,
 Bridgeport, Conn., a corporation of Connecticut

Application October 1, 1937, Serial No. 166,769

11 Claims. (Cl. 1—3)

The invention relates to stapling machines and more particularly to the type which is manually operable to insert and clinch staples.

It is an object of the present invention to provide a stapling device which is rugged, dependable and simple in operation and one which can be made at a very low cost.

According to the present invention, the device is formed of sheet metal parts, most of which are stamped from sheet stock and which are assembled in compact relation. The head for carrying the staple-driving plunger is made up of a plurality of substantially flat strips placed in face-to-face relation, so that a thin plunger carrying head results. The arm for carrying the plunger-carrying head is made up of a pair of nested C-shaped channel members welded together along one side thereof so as to form between the two a channel for the reception of the staples and the staple feed mechanism. The use of the usual pivot and biasing spring for supporting and holding the plunger-carrying arm in raised position has been avoided and the arm is secured directly to the base on a resilient portion thereof in such a manner as to be normally held in raised position but movable into work-engaging position. By securing the plunger-carrying arm directly to the base, a more rigid unit is attained and the side play attendant to the wear of the pivot is avoided.

The elements of the machine, being of sheet metal, can be readily formed and assembled with a minimum of operations and a minimum amount of time, thus reducing considerably the cost of manufacture of the device.

Other features and advantages of the invention will be apparent from the specification taken in connection with the drawings, in which:

Figure 1 is a side elevation of the device.
 Fig. 2 is a front elevation of the device.
 Fig. 3 is a longitudinal section of the device.
 Fig. 4 is a sectional view taken along line 4—4 of Fig. 3.
 Fig. 5 is a sectional view taken along lines 5—5 of Fig. 3.

Fig. 6 is a sectional view taken along line 6—6 of Fig. 3.

Fig. 7 is a sectional view of the device showing the plunger-carrying arm being moved into work-engaging position.

Fig. 8 is a sectional view of the device with the staple-driving plunger moving the staple into engagement with the work.

Fig. 9 is an exploded view of the device show-

ing the elements tied together by dot-and-dash lines.

Fig. 10 is a view showing the type of staples used in the machine.

According to the present invention, a base 20 is stamped from sheet metal and formed to present a flat raised surface. This surface has formed therein, adjacent the forward end, an anvil 21 for clinching the staples to be driven. At the back end of the base a portion 22 is lanced out and bent so as to extend above the base to receive the plunger-carrying arm and resiliently hold the same in raised position out of engagement with the work but because of its resiliency will enable the plunger-carrying arm to be moved into work-engaging position as will be later described.

The plunger-carrying arm of the present invention is formed by nesting together two C-shaped channels 23 and 24 of different dimensions as shown in the drawings, and securing them along the side opposite the opening of the C. This may be done by spot welding or other means. The channels are so shaped that when nested together they form a staple-receiving passage for reception and storage of the staples to be fed successively to the staple-driving plunger. The staples may be in the form of a strip of staples 27, as shown in Fig. 10, in which the staples are readily separated from the strip by the action of the plunger. The rearward end of the inner channel 24 extends a short distance beyond the end of the channel 23 so as to form a guide whereby the staples can be readily inserted into the staple-receiving space. The composite arm is secured at one end to the tang 22 by a pair of rivets 26. The other end of the C-shaped channel 23 is provided with a pair of integrally formed outturned ears 25, which are adapted to be secured to the plunger-carrying head to secure it to the arm. With the arm secured directly to the lanced-out portion of the base, the use of the usual pivot for the arm and the spring for normally holding the arm in raised position is avoided and the resulting structure is very rigid and free from any side play which results when an attempt to produce satisfactory pivots for the arm at a low cost is made.

The plunger-carrying head of the present invention is formed of flat stock stamped to the desired shape and is readily assembled in face-to-face relation to form a plunger-carrying head which is thin and flat and which may be readily secured together by welding or other means. The plunger-carrying head comprises a flat face plate

28, a pair of spaced plates 29 and a back plate 30. The plates are so proportioned that when assembled, the spacer plates, the face plate and back plate form a channel for receiving a thin flat staple-driving plunger 31, the width of the head being equal to the width of the two spacer plates plus the width of the plunger.

5 The staple-driving plunger is provided with an operating handle 32 formed from a flat strip of 10 sheet metal bent into a closed loop with the ends secured together and riveted to the back surface of the staple-driving plunger by a pair of rivets 33.

15 The face plate 28 is provided at its upper edge with a recess 34 stamped therein for receiving the turned-over heads of the rivets when the plunger is moved into staple-driving position. The back plate has a portion cut out from its upper edge to form an opening 35 adapted to receive the part of the handle secured to the plunger.

20 The face plate has at its lower end a portion cut away to form an opening 36. The opening is positioned at the end of the plunger-carrying 25 arm as shown in Fig. 3 and is of such size that the face plate extends over the space formed in the arm to receive the staples so that the face plate forms a stop against which the staples are 30 pressed by the staple-feeding means, to be described, when the plunger is in raised position. The opening permits the user of the device to readily view the work so that the staple may be accurately located and also permits the extraction of staples which may be jammed for any 35 reason whatsoever.

The face plate 28 has intermediate its ends a tang 37 struck therefrom and extending to the rear thereof and adapted to pass through a slot 38 formed in the plunger and into an aperture 39 40 in the back plate which supports the free end of the tang. This tang, operating in the slot, provides a stop for limiting the movement of the plunger in the head.

45 The back plate 30 is formed with a projecting portion whereby the head may be anchored to the arm. This projecting portion is formed by slitting the sides of the backing plate inwardly from the sides so that the uncut portion is equal to the width of the plunger-carrying arm. This 50 section is bent outwardly and the parts formed by the slits are bent downwardly so as to form a rearwardly-extending saddle-like member composed of an upper or top of the saddle 40 and a pair of sides 41 which are adapted to fit over the 55 channel 23 and be secured thereto by welding in the spots indicated by the stippling, in Fig. 9. As will be seen from the drawings, the ears 25 will extend into engagement with the spacer plates to be secured thereto and the sides 41 will 60 not only engage and be secured to the sides of the channel but will abut the back of the ears 25 so that a rigid and durable connection between the plunger-carrying head and the arm is obtained.

65 The top of the saddle 40 is provided with a hole 42 in which is secured a post 43 extending parallel to the staple-driving plunger. The handle 32 has extending therefrom to the rear of the driving plunger one end of the handle material which 70 forms an abutment 44. The abutment 44 is provided with an aperture 45 and the handle is provided with another aperture 46 which is aligned with the aperture 45 and both of which slidably receive the post. A spring 47 is positioned between the top of the saddle and the abutment

and normally tends to hold the staple-driving plunger in raised position.

The spring is of sufficient strength that it will hold the plunger in raised position during the initial pressure on the handle as shown by the 5 arrows A in Fig. 7, which will move the arm into work-engaging position against the resiliency of the lanced-out portion 22. Additional pressure, as indicated by the arrows B in Fig. 8, will compress the spring 47 and cause the plunger to drive 10 the staples against the anvil so that they will be clinched in the work.

The mechanism for successively feeding the staples into driving position is of the well-known type comprising a guide rod 50 having a hooked 15 portion 51 at one end thereof adapted to be inserted into an aperture 52 formed in the two channels and the base as shown in Fig. 3. A staple contactor 53 is shaped so as to slide in the storage space between the two nested C-shaped 20 members and engage the back of the strip of staples. The contactor is adapted to be slidably mounted on the guide. According to the present invention, a U-shaped member 54 is inserted through a pair of holes in the top of the contactor and secured thereto with the legs extending upwardly therefrom. The legs have apertures for slidably receiving the guide 50, and the contactor is held from sliding off the guide by the end of the guide being headed over as shown at 30 55. The staple contactor is biased to slide along the rod 50 and move the staples against the face plate by a spring 56 surrounding the guide rod and abutting against the hooked end at one end and one of the legs on the contactor at the other 35 end.

The exploded view in Fig. 9 clearly shows the simplicity of the device. It shows the elements ready to be assembled with the dot-and-dash lines tying the elements together. This view shows the head positioned to be assembled with the welding points being stippled. From this view it will be seen that the parts can be readily formed by stamping and be easily assembled into completed form with the minimum of operations 45 so that a durable, reliable and inexpensive stapling device will be obtained.

Variations and modifications may be made within the scope of this invention and portions of 50 the improvements may be used without others.

I claim:

1. In a machine for inserting and clinching metallic staples, the combination of a base having 55 as an integral part thereof a flexible portion; a plunger-carrying arm secured to the flexible portion of the base so as to be normally held out of but movable into work-engaging position; and a staple-driving plunger carried by the arm.

2. In a machine for inserting and clinching metallic staples, the combination of a sheet metal base having an integral flexible tang extending angularly therefrom, the free end of said tang normally projecting above the upper surface of the base; a plunger-carrying arm secured to said tang so as to be normally held out of but movable into work-engaging position; and a staple-driving plunger carried by the arm.

3. In a machine for inserting and clinching metallic staples, the combination of a sheet metal base having an integral resilient tongue projecting angularly therefrom; a plunger-carrying arm secured to the tongue and normally carried by said tongue out of work-engaging position, the resiliency of the tongue permitting the arm 70 75

to be moved into work-engaging position; and a staple-driving plunger carried by the arm.

4. In a machine for inserting and clinching metallic staples, the combination of a base; an oscillatable arm mounted on the base; a thin flat plunger-carrying head adapted to be mounted on the ends of the arm comprising a face plate, a back plate and thin spacer plates, the back plate being provided with a rearwardly-extending saddle adapted to fit over and be secured to an end of the oscillatable arm to secure the head to the arm; and a staple-driving plunger carried by the head.

5. In a machine for inserting and clinching metallic staples, the combination of a base; an oscillatable arm mounted on the base; a thin flat plunger-carrying head adapted to be mounted on the end of the arm comprising a face plate, a back plate and thin spaced plates; a staple-driving plunger in the head; the back plate being provided with a rearwardly-extending saddle adapted to fit over an end of the oscillatable arm to secure the head to the arm, the upper surface of the saddle being provided with an aperture; a post secured in the aperture and extending parallel to the plunger-carrying head; and a spring surrounding the post and normally urging the staple-driving plunger into raised position.

30 6. In a machine for inserting and clinching metallic staples, the combination of a base; an oscillatable arm mounted on the base; a plunger-carrying head adapted to be mounted on the end of the arm; a plunger mounted in the plunger-carrying head and having a handle comprising a loop of strip sheet metal with the ends of the loop forming a projection whereby it is secured to the plunger with one of the ends being projected to form an abutment; a post secured to the head and positioned so as to extend parallel to the plunger; and a spring surrounding the post and abutting the abutment formed on the handle to normally hold the plunger in raised position.

45 7. In a machine for inserting and clinching metallic staples, the combination of a base; an oscillatable arm mounted on the base; a plunger-carrying head adapted to be mounted on the end of the arm; a plunger mounted in the plunger-carrying head and having a handle comprising a loop of strip sheet metal with the projecting ends of the loop forming a projection means whereby it is secured to the plunger with one of the ends being projected to form an abutment; a post secured to the head and positioned so as to extend parallel to the plunger; and a spring surrounding the post and abutting the abutment formed on the handle to normally hold the plunger in raised position, said handle and abutment being provided with aligned apertures to receive the post when the plunger is depressed and the spring compressed.

8. In a machine for inserting and clinching metallic staples, the combination of a base; an oscillatable arm mounted on the base; a thin flat

plunger-carrying head on the end of the arm comprising a face plate, a back plate and thin spacing members positioned between the face plate and back plate and forming a guide channel therein; and a thin flat plunger moving in the channel formed in the head by said plates, the plunger having a longitudinal aperture, and the face plate having an integral finger extending through the aperture in the plunger and into an aperture formed in the back plate for positively limiting the stroke of the plunger.

9. In a machine for inserting and clinching metallic staples, a sheet metal base having an integral resilient part; a plunger-carrying arm comprising two sheet metal C-shaped channels secured in nested relation to the resilient part of the base; and a plunger-carrying head secured to the arm, one of the channels being formed with out-turned ears adapted to be engaged by the head whereby the same may be secured to the arm.

10. In a machine for inserting and clinching metallic staples, the combination of a sheet metal base having a resilient tongue extending therefrom; a plunger-carrying arm comprising a pair of C-shaped sheet metal channels nested to form a staple-receiving and supporting passage secured to the resilient tongue; a plunger-carrying head mounted on the arm comprising a sheet metal face plate, a sheet metal back plate and a pair of sheet metal spacer plates interposed between the face plate and back plate and forming a channel in the head; a sheet metal staple-driving plunger movable in the channel in the plunger-carrying head; a handle secured to the plunger comprising a loop of strip sheet metal; means normally tending to move the plunger into raised position in the head; and initial pressure on the handle moving the arm against the resiliency of the tongue so that it moves into work-engaging position and further pressure on the handle overcoming the tendency of the last-named means so that the staple-driving plunger moves into staple-driving position.

11. In a machine for inserting and clinching metallic staples, the combination of a sheet metal base having a resilient tongue projecting therebetween; a plunger-carrying arm secured to the tongue and normally held out of work-engaging position, the resiliency of the tongue permitting the arm to be moved into work-engaging position; a staple-driving plunger carried by the arm, the plunger-carrying head comprising a sheet metal face plate, a sheet metal back plate, and a pair of sheet metal spacer plates interposed between the face plate and the back plate and forming a channel in the head; a sheet metal staple-driving plunger mounted in the channel in the plunger-carrying head; a handle for the plunger comprising a loop of strip sheet metal secured to the upper end of the plunger; and means normally tending to move the plunger into raised position in the head.

CERTIFICATE OF CORRECTION.

Patent No. 2,223,322.

November 26, 1940.

JOHN T. KILBRIDE.

It is hereby certified that error appears in the printed specification of the above numbered patent requiring correction as follows: Page 1, second column, line 25, for "nester" read --nested--; page 3, first column, line 52, claim 7, strike out the word "projection"; and that the said Letters Patent should be read with this correction therein that the same may conform to the record of the case in the Patent Office.

Signed and sealed this 14th day of January, A. D. 1941.

Henry Van Arsdale,
(Seal) Acting Commissioner of Patents.
